SHOE RACK

Charles Turner Jones, Leicester, England, assignor to United Shoe Machinery Corporation, Paterson, N. J., a corporation of New Jersey

Application November 13, 1931, Serial No. 574,831
In Great Britain November 18, 1930

4 Claims. (Cl. 211—34)

This invention relates to racks and is illustrated as embodied in a shoe rack of a type used for holding and transporting shoes during their manufacture.

5 A typical example of racks of the type referred to is disclosed in United States Letters Patent No. 1,556,425, granted October 6, 1925, upon an application filed in the name of W. E. Coombes et al., and disclosing a rack comprising a plurality of paddle pins constructed and arranged to support shoes between operations performed upon the shoes and while the shoes are moved from one place of operation to another. In making use of such racks, it is customary to place 10 upon the racks lots of partially completed shoes and successively to locate the racks in position adjacent to a machine or work bench within reach of the operator who is to perform an operation upon the shoes. The operator then usually 15 picks up a shoe from a rack so located, performs an operation upon the shoe, and returns it to the rack, this being repeated until all of the shoes in the rack have been operated upon. The rack is then removed, another rack is advanced to the 20 place of operation, and the cycle is repeated. In handling shoes in the manner above outlined the movements of the operator in picking up a shoe from a rack and returning it to the rack, repeated hundreds or perhaps thousands of times during 25 a day, will consume a substantial amount of time and will require considerable effort. Consequently, it is desirable to expedite, as much as possible, the operation of handling the shoes. In view of the foregoing, it is an object of the present invention to provide a shoe rack use of which, 30 without sacrificing any of the advantages of shoe racks as heretofore constructed, will facilitate the handling of shoes.

To this end, the illustrated embodiment of the 35 invention comprises, in a shoe rack of the type referred to, a series of shoe-supporting members, successive members of the series throughout the length of the rack being shaped to provide shoe-receiving recesses which converge at one side of 40 the rack so that shoes carried upon the members in the recesses will extend toward a common point. This construction is advantageous in that an operator in performing an operation upon a lot of shoes usually stands in a definite position 45 relatively to a machine or to a work bench, and, when a rack, constructed as above set forth, is so located that the shoe-receiving recesses converge toward the point where the operator stands, the removal and replacement of the shoes are greatly 50 expedited in that the operator can readily grasp 55

any shoe in the rack by rotating his body slightly and by extending his arm in the direction of the shoe, the shoe being withdrawn by a natural movement of the arm substantially in a straight line toward the operator's body. Thus the distance through which the shoes are moved and consequently the effort required to move them are materially reduced, thereby contributing to the efficiency of the operator.

Other objects and features of the invention will 60 be apparent from the accompanying detailed description when taken in connection with the drawing and will be pointed out in the claims.

In the drawing,

Fig. 1 is a plan view of a shoe rack embodying 70 the invention; and

Fig. 2 is a cross-sectional view taken along lines II—II of Fig. 1.

As illustrated in the drawing, the rack comprises vertically extending frame members 10 75 formed of channel sections secured together at the ends of the rack by braces 12, one of which is shown in Fig. 2, and by inclined channel members 14, which are joined by spaced longitudinal members 16. Carried by the frame members is an inclined wooden shelf 18 preferably comprising a plurality of sections 20 which rest upon the members 16 and are secured thereto by screws 22. Extending longitudinally of the rack and to the rear of the sections 20 is a back rail 24 which 80 serves to prevent articles from sliding off the top of the shelf due to its inclination. The sections 20 are provided with reduced, outwardly extending, flat, paddle-shaped portions 26 which are arranged in a series extending longitudinally of the rack and each of which constitutes a shoe-supporting member or pin. The shoe-supporting members or pins 26 have curved, beveled, side edge portions 28, conforming generally to the shapes of the side portions of uppers 85 of shoes to be carried in the rack. Each of the edge portions 28, in conjunction with the edge portion of the next adjacent member, serves to support opposite sides of a shoe positioned between the members bottom side up. The edge 90 portions 28 are spaced to form recesses 30 for the reception of shoes, such as shoe 32, side portions of which are engaged by the said edge portions 28. The shoe-supporting members 26 extend in different directions angularly of the longitudinal axis of the rack, so that the members extend in directions which converge on one side of the rack. The shoe-receiving recesses 30 also converge, the edge portions 28 of the members 26 being so shaped as to define recesses the axes of which 100

converge at a common point at one side of the rack. As a result of this, the longitudinal axes of shoes positioned upon the members in the recesses are directed toward a common point at one 5 side of the rack so that, when a shoe is to be placed on the supporting members 26 or removed therefrom, it can be moved substantially in a straight line toward or from the common point.

In order to raise the foreparts of the shoe 10 slightly above the surface of the shelf 18, thereby to assist in the positioning of the shoes upon the supporting members, there is provided a toe rest 34 extending across the shelf and slightly to the rear of the recesses 30. The toe rest is held in 15 position by dowels 36 which engage the walls of slots 38 in the shelf. To provide for the carrying of small shoes, the shelf also has a pair of slots 40 positioned forwardly of the slots 38 and in which the dowels 36 can be positioned to locate the toe 20 rest 34 in a position in advance of that shown in Fig. 1.

In supporting a shoe upon the rack, the shoe is positioned in the rack bottom-up with the top of the shoe located in one of the recesses 30 with the 25 toe portion resting upon the toe rest 34 and with the opposite sides of the forepart in engagement with edge portions 28 of adjacent members 26. When so positioned the shoe will be held against lateral movement, thereby preventing likelihood 30 of such contact with adjacent shoes as would injure them. The inclination of the members 26 assists in retaining the shoes in the rack during movement of the latter.

In the use of the rack, the operator places the 35 rack near a machine or work bench where an operation upon the shoes is to be performed and so locates the rack relatively to the position in which he stands that his body is substantially at the point of convergence of the recesses. He is 40 then in position readily to reach and to grasp a shoe supported upon members 26 in any of the recesses 30 merely by turning his body slightly and

can move the shoes one at a time substantially in a straight line toward and from the positions in which they are carried in the rack with the result that the positioning of shoes in the recesses and the removal of shoes from the rack for operation upon them can be accomplished with comparatively little effort.

Having described my invention, what I claim as new and desire to secure by Letters Patent of the United States is:—

1. A shoe rack comprising a frame, a plurality of shoe-supporting members carried by the frame, each of the members having edge portions defining shoe-receiving recesses the axes of which converge toward a common point at one side of the rack to facilitate removal of shoes carried by the members in the direction of the point.

2. A shoe rack comprising a frame and a series of shoe-supporting members carried by the frame, successive members of the series throughout the length of the rack being shaped to provide shoe-receiving recesses which converge with respect to each other at one side of the rack.

3. A shoe rack comprising a frame and shoe-supporting members carried by the frame and having each spaced edge portions cooperating with the edge portions of adjacent members to engage shoes carried in the rack, said edge portions being so shaped that the shoes carried thereby throughout the length of the rack are positioned with their axes converging toward a common point located at one side of the rack.

4. A shoe rack comprising a frame and a plurality of shoe-supporting members mounted in the frame, each of said members having an edge portion constructed and arranged to engage one side of a shoe carried in the rack bottom up and so related to the edge portions of the other members that the axes of all the shoes carried by the members will converge toward a point at one side of the rack.

CHARLES TURNER JONES.
